UNITED STATES PATENT OFFICE.

CHARLES M. BOWMAN, OF LEBANON, PENNSYLVANIA, ASSIGNOR OF FOUR-TENTHS TO
GEORGE S. BOWMAN AND THREE-TENTHS TO FRANK P. HAMMAR, OF LEBANON,
PENNSYLVANIA.

KNOCKDOWN METALLIC SHIPPING OR STORAGE RECEPTACLE.

1,147,073.

Specification of Letters Patent. Patented July 20, 1915.

Application filed February 12, 1914. Serial No. 818,256.

To all whom it may concern:

Be it known that I, CHARLES M. BOWMAN, a citizen of the United States, residing at Lebanon, in the county of Lebanon and 5 State of Pennsylvania, have invented certain new and useful Improvements in Knockdown Metallic Shipping or Storage Receptacles; and I do hereby declare the following to be a full, clear, and exact 10 description of the invention, such as will enable others skilled in the art to which it app pertains to make and use the same.

My invention relates to metallic shipping and storage receptacles, has especial reference 15 to that class of receptacles known to the trade as "knockdown", has for its object a cheap, and durable receptacle which can be used repeatedly for shipping or storage purposes, and the invention consists in 20 certain improvements in construction, which will be fully disclosed in the following specification and claim.

In the accompanying drawings, which form part of this specification:—Figure 1 25 is a side elevation of a metallic shipping or storage receptacle, set up and ready for shipping or storage purposes. Fig. 2 is an end view of the body of the receptacle, partly expanded and in condition for nesting purposes for shipment. Fig. 3 is a side elevation of one end of the receptacle in the same condition shown in Fig. 2. Fig. 4 is an end view with the top of the closure removed. Fig. 5 is an enlarged detail in section, illustrating the manner of securing the closure to the body of the receptacle, and 35 Fig. 6 is a transverse section on line 6—6 Fig. 3.

Reference being had to the drawings and 40 the designating characters thereon, the numeral 1 indicates the body of a metallic shipping or storage receptacle, preferably made of corrugated sheet metal, provided at its upper and lower ends with interlocking 45 straps 2, 3, formed integral with the body 1, which enter openings or slots 4, in the ends of the body, are bent at 5, over the projections or members 6, formed integral with the body 1, are pressed down and form 50 a lock joint.

To the upper and lower ends of the re-

ceptacle are additional locking straps 7, which may be formed integral with the body 1, or may be made of separate pieces of material secured to the body 1. 55

The receptacle is provided with a closure 8, having openings 9 to receive the locking straps 7 which after passing through said openings 9 are bent over at 10 and through openings 11 in the rim 12 of the closure 8 60 and are then turned over the edge of the bead 13 on the rim of the closure, thus making a double locked joint.

In making my receptacle, I first take sheet metal of a length and width suitable for the 65 size of the receptacle determined upon, and by means of a suitable die or other implement, stamp out the locking straps 2, 3 and 7 and the slots or openings 4 in the body of sheet metal. The sheet metal is 70 then bent into the form of a cylinder with the adjacent edges overlapping each other as shown in Fig. 6 with the corrugations intermeshing, when the locking straps 2, 3 are inserted in slots or openings 4 and bent 75 back upon the members 6, thus forming a perfect joint, capable of resisting internal pressure and which may be subsequently unfolded, the longitudinal joint of the receptacle released, if desired and a number of 80 receptacles nested and returned for subsequent use. The free edge of the outside overlapping member of the side joint of the body of the receptacle engages the inner ends of the straps 2, 3, and forms a seat for 85 the same and thereby regulates the extent of the overlapping joint.

Having thus fully described my invention, what I claim is:

A metallic shipping or storage receptacle 90 comprising a body, end closures for the body having flanges snugly fitting the outer contour of the same, radial flanges formed at right angles to said first mentioned flanges, and straps for securing said closures 95 to said body, one end of said straps being secured to the inner wall of said body, the other end of said straps being passed through openings formed in said closures, trained over the outer wall of the closures 100 and over the outer wall of said first mentioned flanges, passed downwardly through

openings formed in said radial flanges immediately adjacent the juncture thereof with said first mentioned flanges, trained outwardly under said radial flanges and bent up and over the edges thereof and into locking engagement with the upper face of said radial flanges.

Copies of this patent may be obtained for five cents each, by addressing the "Commissioner of Patents, Washington, D. C."

In testimony whereof I affix my signature, in presence of two witnesses.

CHARLES M. BOWMAN.
